236,002

EMISSION ELECTRODE FOR AN ELECTROSTATIC PRECIPITATOR

Kjell Porle and Sten Maartmann, Vaxjo, Sweden, as-
signors to Aktiebolaget Svenska Flaktfabriken, Nacka,
Sweden

Filed Oct. 17, 1973, Ser. No. 407,312

Term of patent 14 years

Int. Cl. D13—03

U.S. Cl. D26—1 L

Fig. 2

Fig. 1

Fig. 3

FIG. 1 is a front view of an emission electrode for an electrostatic precipitator showing our new design;

FIGS. 2 and 3 are respectively right and left side elevational views thereof;

FIGS. 4 and 5 are respectively top and bottom plan views thereof;

FIG. 6 is a rear view thereof; and

FIG. 7 is a perspective view thereof.

We claim:

The ornamental design for an emission electrode for an electrostatic precipitator, substantially as shown and described.
